UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE FOR RAILWAY-CARS.

1,366,676.

Specification of Letters Patent. Patented Jan. 25, 1921.

Application filed September 25, 1919, Serial No. 326,125. Renewed December 18, 1920. Serial No. 431,786.

To all whom it may concern:

Be it known that I, JOHN F. O'CONNOR, a citizen of the United States, residing at Chicago, in the county of Cook and State of Illinois, have invented a certain new and useful Improvement in Hand-Brakes for Railway-Cars, of which the following is a full, clear, concise, and exact description, reference being had to the accompanying drawings, forming a part of this specification.

This invention relates to improvements in hand brakes for railway cars.

The object of the invention is to provide a hand brake suitable for railway freight cars and wherein is obtained a high leverage ratio, the parts being compactly arranged and easily operable in the usual manner.

In the drawings forming a part of this specification, Figure 1 is a top plan view of a hand brake of the vertical staff type showing my improvements in connection therewith, a portion of a car end wall being indicated to bring out the position of the brake with respect thereto. Fig. 2 is a vertical sectional view upon an enlarged scale taken on the line 2—2 of Fig. 1, parts being broken away in order to prevent crowding of the drawing. Figs. 3 and 4 are horizontal sectional views taken on the lines 3—3 and 4—4, respectively, of Fig. 2. And Fig. 5 is a detail elevational view to illustrate the locking dog employed with my improvements.

Fig. 6 is a view similar to Fig. 1 and illustrates another embodiment of the invention. Fig. 7 is a vertical sectional view taken substantially on the line 7—7 of Fig. 6. And Fig. 8 is a horizontal sectional view taken on the line 8—8 of Fig. 7.

Referring first to the construction illustrated in Figs. 1 to 5, inclusive, 10 denotes the end wall of a gondola or other freight car and 11 a vertical brake staff such as is ordinarily used on freight cars. On the upper end of the staff 11 is rotatably mounted a hand wheel 12 of usual diameter and rim so that the brakeman is enabled to operate it in the usual manner. Said hand wheel 12 is provided with a hub 13 which is loosely rotatably mounted on the rounded section 14 of the staff, the hand wheel being prevented from accidental removal by any suitable means—such as the washer 15 and nut 16.

The hub 13 is in turn rotatably mounted

in a bushing or sleeve 17, the latter having a depending rim 18 which fits over an upstanding flange 19 formed on the bracket 20, the latter being riveted to the wall of the car. The sleeve 17 is arranged concentric with the internal gear 25 and the hub 13 is rotatably mounted within said sleeve 17, as clearly indicated in Fig. 3. The bearing for the rounded section 14 of the staff 11 provided in the hub 13 is, however, eccentric, as appears from Fig. 3, the function for this construction being explained hereinafter. The hub 13 is provided with a radial lug 21 which works in an arcuate slot 22 provided in the sleeve 17 so that the hub 13 is permitted a limited amount of rotation with respect to the sleeve 17 and sufficient to bring the bearing for the staff 11 concentric with the axis of the sleeve 17.

Below the hub 13, the staff 11 is provided with a squared section indicated at 23, on which is non-rotatably mounted a pinion 24. The teeth of the pinion 24 mesh with an internal fixed gear 25 of larger diameter, the gear 25 being concentric with the sleeve 17, so that, when the hub 13 and the bearing for the upper end of the staff 11 are rotated so as to bring the axis of the staff 11 into coincidence with the axis or center of the internal gear 25, the pinion 24 will thereby be disengaged from the internal gear 25.

The sleeve 17, at its lower end, is provided with a horizontal radially-extending flange 26, the underface of which is provided with a series of radially-extending teeth 27 to act as a ratchet wheel. Coöperable with said teeth 27 is a gravity controlled dog 28 pivotally mounted on a stud 29 cast integral with the upstanding flange 19 of the bracket 20.

The operation is as follows: Assuming the parts as shown by the full lines in Figs. 1, 2, 3 and 4, to wind up the brake chain, the brakeman turns the hand wheel 12 in the direction indicated by the arrow *a* in Fig. 1. In this condition, it will be noted that the lug 21 of the hub 13 is bearing against the corresponding shoulder 121 of the sleeve 17, and, consequently, the sleeve 17 will be moved in unison with the rotation of the hand wheel 12. This causes the pinion 24 to roll along the internal gear 25 and remain enmeshed therewith. Due to the difference in number of teeth on the pinion 24 and internal gear 25, it is evident that relative

tive rotation between said pinion and internal gear will take place, the amount of relative rotation depending upon the difference in number of teeth. In the drawing I have shown approximately forty teeth in the internal gear and approximately thirty on the pinion 24, so that, for a complete revolution of the hand wheel 12, the staff 11 will be rotated in the reverse direction—that is, 10 counter-clockwise—approximately one-third of a revolution. With this differential planetary gearing, it is evident that the leverage ratio is appreciably multiplied and may be made as great as desired, consistent 15 with the necessary speed in winding up the brake chain. The gravity dog 28 will automatically coöperate with the teeth 27 of the ratchet wheel and prevent any possible accidental release of the parts. To effect release of the brake chain, the brakeman merely turns the hand wheel 12 in the reverse direction—that is, counter-clockwise—which will permit the hub 13 to rotate with respect to the sleeve 17 a distance corresponding to the length of the arcuate slot 22. As this relative rotation between the hub 13 and sleeve 17 occurs, the pinion 24 is disengaged from the internal gear 25, thereby leaving the staff 11 free to rotate under the 30 tension on the brake chain. To again wind the chain, the brakeman rotates the wheel 12 in the usual manner and there will be a short period of lost motion while the lug 21 is traveling in the arcuate slot 22, after 35 which operation is as above described.

In the construction illustrated in Figs. 6, 7 and 8, the arrangement is much the same except that no provision is made for disengaging the pinion from the internal gear, 40 and to release the brake chain, the brakeman is required to rotate the hand wheel in a direction the reverse of that employed in the winding operation.

In said Figs. 6, 7 and 8, the hand wheel is 45 designated as 112 and has a depending flange 113 serving as a hub, said flange 113 being loosely rotatably seated on an upstanding flange 119 formed integral with the bracket 120. The hand wheel 112 has a bearing, indicated at 40, for the upper circular section 114 of the staff 111, which bearing 40 is eccentric with respect to the hub flange 113.

Below the circular section 114, the staff is 50 provided with a squared section 123 on which is non-rotatably mounted a pinion 124, said pinion meshing with an internal stationary gear 125 formed on the inner side 55 of said flange 119.

The hub flange 113 is provided along its 60 under surface with a series of radially-arranged teeth 127, with which coöperates a gravity controlled pivoted dog 128 having a release handle 41.

The operation is as follows: To wind up 65 the brake chain, the hand wheel 112 is ro-

tated in the direction indicated by the arrow *b*—that is, clockwise. This causes the eccentrically mounted staff to travel with its pinion 124 around the internal gear 125, thereby causing relative rotation between 70 the gear 125 and the pinion 124. The amount of relative rotation, of course, depends upon the difference in the number of teeth between the pinion and the gear, which may be made as small or as great as 75 desired to obtain the necessary leverage ratio. As a precautionary measure, the dog 128 is employed to retain the wheel against accidental reverse rotation. To release the 80 locking dog 128 and rotates the hand wheel in a counter-clockwise direction until the necessary slack in the chain has been obtained.

I claim:

1. In a brake of the character described, the combination with a vertical staff having a pinion rotatable in unison therewith, of a fixed internal gear surrounding and coöperable with said pinion, and means for 90 swinging the pinion around said gear to thereby produce a differential action between the pinion and gear and thus rotate the staff.

2. In a brake of the character described, 95 the combination with a brake staff and a bracket arranged to be attached to the wall of a car, of an internal gear fixed with respect to said bracket, a pinion rotatable in unison with the staff and a manually operated member rotatably mounted on the bracket and rotatable about the same axis as that of said gear, said member having an eccentric bearing for the staff.

3. In a brake of the character described, 105 the combination with a vertical brake staff, of a hand wheel having a hub provided with an eccentric bearing for the upper end of said staff, a stationary internal gear with its axis coinciding with the axis of rotation of 110 the hand wheel, and a pinion of a lesser number of teeth than said gear and fixed on the staff and coöperable with said internal gear.

4. In a device of the character described, 115 the combination with a vertical brake staff and a hand wheel, of a system of planetary gears interposed between said hand wheel and the staff including, one gear fixed to the staff, and means for effecting the release of 120 said gears to render them inoperative and thereby release the staff.

5. In a brake of the character described, the combination with a brake staff, and a bracket arranged to be attached to the wall 125 of a car, of an internal gear fixed with respect to said bracket, a pinion rotatable in unison with the staff and a manually operated member rotatably mounted on the bracket and rotatable about the same axis as 130

that of said gear, said member having an eccentric bearing for the staff, and means co-operable with said member and the bracket for shifting the bearing of the staff to a position concentric with the gear to thereby release the staff.

6. In a brake of the character described, the combination with a fixed bracket and a vertical brake staff, of a hand wheel loosely 10 rotatably mounted on the top of the staff, said hand wheel providing an eccentric bearing for the upper end of the staff, a pinion mounted on said staff to rotate in unison therewith, and a fixed internal gear with 15 which said pinion co-operates, said hand wheel being rotatable about an axis coinciding with the axis of the internal gear.

7. In a hand brake for railway cars, the combination with a bracket secured to a car

wall and having a fixed internal gear, of a 20 vertical brake staff having a pinion near the upper end thereof rotatable in unison with the staff, said pinion normally meshing with said internal gear, a hand wheel having a hub, said hand wheel and hub being 25 rotatable about an axis coinciding with the axis of said internal gear, said hub having an eccentric bearing for the staff and a member loosely rotatably mounted on said bracket about an axis coinciding with the 30 axis of the internal gear, said hub and member having a predetermined amount of lost motion therebetween to thereby permit shifting of the eccentric bearing of the staff.

In witness that I claim the foregoing I 35 have hereunto subscribed my name this 8th day of Sept., 1919.

JOHN F. O'CONNOR.
